UNITED STATES PATENT OFFICE

CHARLES H. MILLER, OF HOLLIDAYS COVE, WEST VIRGINIA

CHRISTMAS ORNAMENT

Application filed June 29, 1931. Serial No. 547,769.

This invention appertains to new and useful improvements in ornaments, and more particularly to an ornament especially devised for use at Christmas time.

5 The principal object of this invention is to provide an ornament wherein the usual Christmas tree balls can be used in artistic arrangement by novel means for connecting the same to the base structure.

10 During the course of the following specification and claims, other important objects and advantages of the invention will become apparent to the reader.

In the drawing:—

15 Figure 1 represents a front elevation of the ornament.

Fig. 2 represents a fragmentary front elevational view of the frame work.

20 Fig. 3 represents a cross sectional view through one of the members of the frame work after the balls have been secured in place.

25 Referring to the drawing wherein like numerals designate like parts, it can be seen that the general configuration of this design can be varied, for instance, it can be circular, square, oblong or star-like as represented in the accompanying drawing. In constructing this ornament in a star shape, it is preferable that each point of the star be constructed of a pair of sections, each of which is denoted by numeral 5. However, a circle or square frame could also be constructed in sections or may be constructed in a single integral piece. 30 However, the main feature of the invention is the manner in which the Christmas tree balls are secured to the otherwise finished ornament.

35 In carrying out the invention, each of the sections 5 is provided with a plurality of longitudinally spaced openings 6, each of which is large enough to receive the usual string portion 7 of a Christmas ball 8. Although reference is made to these balls as being of the 40 Christmas tree type, it is to be understood that they may be of some other special construction unlike a Christmas tree ball, but having the general characteristics, such as the attractive bulk and the aforementioned shank 7.

45 After these openings 6 have been formed

in the frame, tracing paper 9 is then wrapped around the frame section, preferably after the conductor wires 10 extending between the sockets 11 have been laid in place against the back side of the frame. With the crepe paper 55 applied, the wires 10 will be on the inside of the paper, that is between the paper and the frame 5 and after this construction, the metallic foil 11 is applied over the crepe paper, with its portions suitably secured together at 60 the back side of the frame.

In now placing the Christmas tree balls on the ornament, the shank 7 of each ball is first dipped or has some adhesive applied thereto, after which the same is pushed through the 65 metallic coil, and crepe paper into a corresponding opening 6, and at this point it is to be observed that while the metallic coil serves to provide a glittering attractive service, the crepe catching some of the adhesive from the 70 shank so that when the adhesive is moistened, a firm connection is established between the paper and the neck of the ball.

75 The sockets 16 may be placed at desired intervals around the frame, and after the crepe paper metallic coils, and balls 8 have been placed on the frame, the internal and external tinsel 12 is applied to the inner and outer perimeters and the outer tinsel may have some imitation icicles 19 depending 80 therefrom as clearly shown in Fig. 1.

Some central ornamental element such as a leaf or the like may be placed in the manner substantially shown in Fig. 1. Obviously, the electric sockets can be done away with, 85 and large balls can be placed at the outer and inner ends of the star points, or on the other hand, with the use of the electric bulbs, Christmas tree balls can be provided, and as another or alternative, large balls and small 90 balls may be used in any attractive arrangement with or without the electric lamp.

A suitable hook 14 can be provided at the upper point of the star, and obviously, while the foregoing specification sets forth the invention in specific terms, it is to be understood that numerous changes in the shape, size, and materials may be resorted to without departing from the spirit and scope of the invention 95 as claimed hereinafter.

Having thus described my invention, what I claim as new is:—

1. An ornament of the character described comprising a base, said base being provided with an opening therein, a ball provided with a shank, a crepe paper covering for the base, adhesive for the shank so that when the shank is pushed through the crepe paper to project into the opening of the base, the adhesive will contact with the crepe paper.

10 2. An ornament of the character described comprising a base, said base being provided with an opening therein, a ball provided with a shank, a crepe paper covering for the base, adhesive for the shank so that when the shank is pushed through the crepe paper to project into the opening of the base the adhesive will contact with the crepe paper, and a metallic foil sheet for disposition around the said crepe paper.

15 3. An ornament of the character described comprising a support having an opening therein, a sheet of rupturable material disposed over the openings, an ornamental member provided with a shank forced through the rupturable sheet to project into the openings.

20 4. A method of constructing ornamental devices consisting in forming an opening in a base, disposing a sheet of rupturable material over the opening in the base and applying a shanked display element by forcing this shank through the sheet and into the opening.

25 5. A method of constructing ornamental devices consisting in forming a base with an opening, disposing a sheet of rough rupturable material over the opening, and applying a display element by forcing a portion thereof through the material and into the opening.

30 6. A method of constructing ornamental devices consisting in forming a base with an opening, disposing a sheet of crepe material over the opening, and applying an ornamental element, by coating a portion thereof with an adhesive and inserting the coated portion through the material and into the opening.

In testimony whereof I affix my signature.
CHARLES H. MILLER.
